UNITED STATES PATENT OFFICE

ROLAND GORBOLD, OF HILLSIDE, GREAT HOUGHTON, ENGLAND

DESIGN FOR A COMBINED SOLE AND HEEL

Application filed September 4, 1928. Serial No. 28,031. Term of patent 7 years.

To all whom it may concern:

Be it known that ROLAND GORBOLD, a subject of the King of Great Britain, a resident of Hillside, Great Houghton, Northampton, England, has invented a new, original and ornamental Design for a Combined Sole and Heel, of which the following is a specification, reference being had therein to the accompanying drawing, forming part thereof.

Fig. 1 is a plan view of a combined sole and heel, showing my new design; and Fig. 2 is a longitudinal cross-sectional view on line 2—2 of Fig. 1.

I claim:

The ornamental design for a combined sole and heel, substantially as shown.

In testimony whereof the petitioner has hereunto affixed his hand and seal.

ROLAND GORBOLD. [L.S.]
